UNITED STATES PATENT OFFICE.

CECIL M. GRIFFIN, OF PITTSBURGH, PENNSYLVANIA.

TUBE-CLEANING TOOL.

Application filed November 1, 1921. Serial No. 512,091.

To all whom it may concern:

Be it known that I, CECIL M. GRIFFIN, a citizen of the United States, residing at Pittsburgh, in the county of Allegheny and 5 State of Pennsylvania, have invented certain new and useful Improvements in Tube-Cleaning Tools, of which the following is a specification.

This invention is for a tool of the general 10 type shown in my United States Letters Patent No. 1,280,443, dated October 1, 1918, for cleaning tubes, particularly tubes in steam condensers or the like.

Tools constructed in accordance with my 15 invention are especially adapted for use in a method of cleaning, wherein the cleaners are forced through the tubes by fluid pressure, and the invention has for its principal objects to provide a tool or cleaner having 20 effective scraping blades thereon which are both strong and flexible, whereby they may yield to conform to irregularities in the tubes, and are less liable to become caught or hung on any such irregularities.

25 Further objects are to provide scrapers which will have a relative long life and are capable of withstanding the rough usage to which tools of this kind are subjected.

To these ends my invention consists, generally stated, of a number of yieldable scrapers mounted on a central body member, the scrapers being so formed and so mounted on the central body member as to give them the desired strength, flexibility, 35 and effectiveness, as hereinafter more specifically described in connection with the accompanying drawings, in which:

Fig. 1 is a side elevation of a tube cleaner embodying my invention;

40 Fig. 2 is a front end view thereof;

Fig. 3 shows a rear end view thereof;

Fig. 4 shows a tube, partly in section and partly in elevation, showing a portion of the tool therein to illustrate the manner of 45 operation of the scrapers.

In the drawings, 5 is a central body member which, for the purpose of reducing the weight of the device, is tubular. Riveted or otherwise secured to the ends of the body, 50 are plugs 6 and 7, plug 6 being at the front and being rounded on its forward end for the purpose of designating the front end so that the operator can readily distinguish the respective ends, the rear face of plug 7 being flat.

Secured one behind another about the

body member 5 are the scrapers. These comprise a series of spaced apart helical coils 8 of spring metal closely fitting about the body 5. The metal from which the coils 60 are made is preferably square or noncircular in cross section, so as to provide corners for effectively scraping the material from tubes. Each coil or helix preferably has more than one complete turn. The front 65 end of the coils are bent inwardly to engage in a hole or recess in the body 5, whereby the coils are held against longitudinal or rotative movement on the body 5 and in proper spaced relation. The other end of 70 the coil is bent outwardly at 9 in such manner that the end portion 10 is held away from the body 5 a sufficient distance to contact with the walls of a tube of a diameter which the tool is constructed and designed 75 to clean. This portion 10 curves to conform substantially to the interior of a tube of a given diameter. The recesses in which the ends of the coils are secured are staggered 80 or offset from each other so that the scraping portions 10 are not all in alinement, but are distributed so that the body will be centered in the tube and the entire inner surface of the tube cleaned. Figs. 2 and 3 of 85 the drawings show how the portions 10 project at all sides, the ends apparently overlapping.

When it is desired to clean a tube, the cleaner is forced or pushed into one end of the tube by an operator, the front end being 90 inserted first. Then a nozzle is held against the end of the tube and the tool is driven through the tube by fluid pressure, preferably water or air, provided through the nozzle. Upon reaching the other end of the tube, the tool falls out and may be again used. In cleaning a condenser, a large number of the tools are employed, so that the different tubes of a condenser may be cleaned 95 in rapid succession, the tools after passing through the tube falling into a heap or pile where they are gathered and returned to the operator. Instead of being driven through the tubes by fluid pressure, a rod of sufficient length may be employed to push them through. The tools are rugged and durable, and are not readily injured by such rough handling and usage.

100 In passing through the tube, the portions 10 of the coils scrape against the interior walls thereof. If irregularities are encountered which the tool could not otherwise

pass, or which it cannot remove, the end portion 10 will yield, being forced inward radially and spread longitudinally as indicated in Fig. 4, in which A is a tube. In 5 this figure, the end portions 10 are shown so displaced as to enable the tool to pass irregularities, and the scrapers are not apt to be injured. Because the scrapers 8 are in the form of a coil having more than one, 10 and preferably almost two complete convolutions, the portion 10 is enabled to be displaced to a greater extent when an irregularity is encountered. The portion of the spring contacting with the body being of 15 substantially the same diameter as the body, it sets firmly on the body 5, thus holding the scraping portion out against the surface to be cleaned, the coil itself not being able to move radially to any appreciable extent.

20 Tools constructed in accordance with my invention can be cheaply and easily made and repaired, the scrapers 8 being replaceable.

25 Various changes and modifications may be made in the specific form of invention shown without departing from the spirit of my invention and within the scope of the appended claims.

I claim as my invention:

- 30 1. A tube cleaning tool comprising a body member having a plurality of spaced apart yieldable scrapers arranged one behind another thereon, said scrapers being formed of helical coils closely fitting the body and secured thereto, a portion of the coils being bent outwardly to yieldably engage a tube.
- 35 2. A tool for cleaning tubes upon being passed through the same comprising helical coils fitted closely about a central body member and arranged one behind another thereon, scrapers formed at and integral with
- 40

the rear ends of said coils, the front ends of the coils being attached to the body.

3. A tool for cleaning tubes upon being passed through the same comprising a body 45 having helical coils fitting closely about a central body member and arranged one behind another thereon, said body having a plurality of holes therein, each of said coils being provided at one end with a scraper 50 and having its other end bent inwardly to engage a hole in said body member to prevent the coil from moving along or around the body member.

4. A tube cleaning tool comprising a central body member, a plurality of resilient coils mounted on the body and longitudinally spaced from one another, said coils fitting relatively close to the body, said coils having corresponding parts thereof bent outwardly beyond the diameter of the remaining portions of the coils to form a relatively small scraping surface, said coils being so arranged on the body that the scraping portions of the series of coils will form in effect an annular scraping surface, so that the entire interior of a tube to be cleaned may be scraped and said body will be centrally positioned in the tube.

5. A tool for cleaning tubes upon being 70 passed therethrough comprising a central hollow body member having the ends thereof closed, and a series of spaced apart yieldable scrapers in the form of coils arranged closely about the body and secured thereon 75 against relative movement, the end portion of each of the coils being offset to yieldingly engage a tube when being passed therethrough.

In testimony whereof I affix my signature.

CECIL M. GRIFFIN.
